(57) **CLAIM**

The ornamental design of a sprayer tank with holster for tools or accessories, as shown and described.

DESCRIPTION

FIG. 1 is a perspective, elevational view taken from the top, right side of a sprayer tank with holster for tools or accessories showing my design;

FIG. 2 is a front elevational view thereof, the rear elevational view being the same;

FIG. 3 is a right side elevational view thereof, the left side view being the same except for the holster;

FIG. 4 is a bottom view thereof; and,

FIG. 5 is a top view thereof.
